UNITED STATES PATENT OFFICE.

JOSEPH J. MARKOVICH, OF UNIONTOWN, PENNSYLVANIA.

RAIL JOINT CHAIR.

1,420,566.

Specification of Letters Patent. Patented June 20, 1922.

Application filed March 4, 1922. Serial No. 541,013.

To all whom it may concern:

Be it known that I, JOSEPH J. MARKOVICH, a citizen of the United States of America, residing at Uniontown, in the county of Fayette and State of Pennsylvania, have invented certain new and useful Improvements in Rail Joint Chairs, of which the following is a specification.

This invention relates to certain new and

useful improvements in rail joint chairs and has particular reference to a combined joint chair and fish plate connected together in a manner to prevent relative movements between the elements.

The primary object of the invention resides in the provision of a rail joint chair wherein rail engaging clamps are interlocked with the joint chair with the usual form of spikes for retaining the rail engaging clamps in their operative positions.

Another object of the invention has reference to a novel form of fish plate associated with the joint chair, the lower edge of the fish plate extending in proximity of the base flange of the rails with means carried by the joint chair inclosing the lower edge of the fish plate.

With the above general objects in view and others that will appear as the nature of the invention is better understood, the same consists of the novel form, combination and arrangement of parts hereinafter more fully described, shown in the accompanying drawing and claimed.

In the drawing, wherein like reference characters designate corresponding parts throughout the several views,

Figure 1 is an elevational view of a joint chair constructed in accordance with the present invention, showing the meeting ends of rails seated in the chair.

Figure 2 is a top plan view of the joint chair and rail engaging clamp retained in operative position by spikes carried by the joint chair.

Figure 3 is a cross sectional view taken on line III—III of Figure 1 showing the rail engaging clamps in their operative positions, with the fish plates anchored to the rail.

Figure 4 is a cross sectional view taken on line IV—IV of Figure 1 showing the lower edge of the fish plate confined within the joint chair.

Figure 5 is a fragmentary perspective

view of the fish plate, showing the base flange and depending lips carried thereby.

Figure 6 is a fragmentary perspective view of the bottom wall of the joint chair, showing the key openings for the reception of the rail engaging clamps and the upturned lips carried by the base plate for engagement with the lower edge of the fish plate.

Figure 7 is a cross sectional view of a modified form of the invention showing a different type of joint chair and fish plate, and a different type of rail engaging clamp,

Figure 8 is a side elevational view of the form of chair shown in Figure 7,

Figure 9 is a detail sectional view showing the form of clamp in the fish plate of the joint chair,

Figure 10 is a detail sectional view similar to Figure 9 with the rail engaging arm of the clamp distorted for sliding permanent mounting in the joint chair,

Figure 11 is a sectional view showing the rail engaging clamp disclosed by Figure 10 in side elevation and in engagement with the base flange of the rail.

Referring more in detail to the accompanying drawing, and particularly to Figures 1 to 6 there is illustrated a joint chair for supporting meeting rail ends 1, the chair embodying a base plate 2 carrying an integral fish plate 3 at one side thereof for engagement with the base flange, webs and adjacent sides of the rail heads, the upper or rail head engaging edge of the plate 3 being of increased cross sectional area as indicated at 4 to provide a reinforcing or bracing structure at the meeting ends of the rails.

As shown more clearly in Figure 2, the base plate 2 of the joint chair carries an outwardly directed anchoring strip 5 at each side of the plate upon the side thereof carrying the integral fish plate 3, the anchoring strips 5 being provided with openings 6 to facilitate the passage of spikes 7 that enter the supporting tie 8 as shown in Figure 3.

The opposite side edge of the base plate 2 carries an outwardly directed anchoring strip 9 at each end thereof, the strips 9 being provided with T-shaped openings 10 having enlarged ends 11 for the reception of the interlocking rail engaging clamps 12.

Each clamp embodies a shank portion having a base block 13 and a clamp head 14 upon

the upper end thereof, the base block 13 being inserted through the enlarged end 11 of the strip 9 and subsequently shifted into the smaller end of the opening 10 to facilitate 5 the positioning of the rails 1. When the rail is properly located in the joint chair, the clamps 12 are moved through the slots 10 in a direction toward the rail to cause the clamps 14 to engage the base flange of the 10 rail, the engaging clamps being retained in position by the spikes 15 entering the extreme outer end of the opening for reception in the tie 8, and thereby anchoring the chair and rails to the tie. As shown in Figure 3, 15 the filler plate 16 is interposed between the base plate 2 of the chair and the tie 8, compensating for the depth of the base block 13 of the rail engaging clamp as will be readily understood.

20 A removable fish plate is associated with the joint chair and the rails, and is positioned at the side of the rails opposite the integral fish plate 3, the removable fish plate embodying a rail web engaging plate 17 of 25 the same length as the joint chair, the plate 17 carrying an outwardly directed extension arm 18 for engagement with the base flange of the rail, with the arm 18 disposed between the chair anchoring strips 9 as shown in 30 Figures 1 and 2 with a depending lip 19 formed at the outer end of the arm 18 for engagement with the outer edge of the rail base flange. As shown more clearly in Figures 1, 2 and 4 the bottom wall 2 of the 35 chair has an upwardly extending lip 20 intermediate the anchoring lip extensions 19, the lip 20 being positioned outwardly of the fish plate lip 19 enclosing the same and co-operating therewith in a manner to prevent 40 outward movement of the fish plate 17 relative to the joint chair. To anchor the plate 17 to the rail and chair, a plurality of registering openings are formed in the integral fish plate 3, the rail webs and the removable 45 plate 17 for the reception of locking bolts 21.

From the above detailed description, it is believed that the construction and operation of the invention as disclosed in said figures will be readily understood. The rail 50 engaging clamps are first inserted in the enlarged ends 11 of the base plate openings 9 to be moved to the outer ends of the openings 10, the meeting rail ends 1 being then disposed in the joint chair with the removable fish plates 17 engaging the rails and disposed in proper relation to the meeting rail ends and anchored thereto by the lock bolts 21, it being noted that the lip extension 19 upon the removable fish plate arm 18 is disposed inwardly of the lip 20 carried by the base of the joint chair intermediate the anchoring strip sections 9. The rail engaging 60 clamps are then moved through the slots 10 in a direction toward the base flanges of the

rails, to cause the clamp heads 14 to engage 65 the rail as shown in Figure 2 spikes 15 being inserted into the outer ends of the openings 10 for engagement with the tie 8 to anchor the joint chair and rails to the tie, it being understood that the spikes 7 inserted through 70 the openings 6 in the anchoring strips 5 will securely bind the chair to the tie at the opposite side thereof. The filler plate 16 interposed between the joint chair and the tie to compensate for the height or depth of 75 the base block 13 of the rail engaging clamp, provides a rigid and substantial mounting for the joint chair and a strong support for the rail. A modified form of the invention is shown in Figures 7 to 11, the fish plates 80 3' being formed integral with the base plate 2' of the joint chair while integrally formed screw bolts 21' for the reception of lock nuts 22 upon the projecting ends thereof, are carried by the fish plate 3' the 85 bolts 21' passing through removable fish plates 17' positioned at opposite sides of the rail. The free edge of the base plate 2' is provided with a series of transversely extending slotted openings 23 undercut at their 90 lower sides as at 24 to provide retaining shoulders for the rail engaging clamps. A rail engaging clamp is shown in detail in Figures 9, 10 and 11, the same embodying 95 a shank portion 25 having a rail engaging 27. The shank 25 of the rail engaging clamp is normally of the form shown in Figure 9, whereby the same may be inserted through the opening 23 of the base plate 2' at the 100 lower side thereof and subsequently flattened or distorted to cause the same to assume the formation shown in Figure 10, the clamp 25 being permanently mounted in the base plate 105 2' of the joint chair for the free sliding movement. When the rail engaging clamp 25 is moved into engagement with the base flange of the rail as shown in Figure 11, a spike 7 or 15 is inserted into the other end 110 of the opening 23 to retain the rail engaging clamp in engaging position with respect to the base flange of the rail.

While there are herein shown and described the preferred embodiments of my invention, it is to be understood that minor 115 changes in construction, combination and arrangement of parts may be made without departing from the spirit and scope of the invention as claimed.

Having thus described the invention, what 120 I claim is:

1. In a joint chair of the type described, a base plate, anchoring strips extending from the opposite sides thereof adjacent the ends, an integral fish plate carried by one 125 side of the base plate, the anchoring strips at one side of the base plate having T-shaped openings therein, rail engaging clamps in-

terlockingly received in the T-shaped openings and means for retaining the clamps in engagement with the rails.

2. In a joint chair of the type described, 5 a base plate, anchoring strips extending from the opposite sides thereof adjacent the ends, an integral fish plate carried by one side of the base plate, the anchoring strips at one side of the base plate having 10 T-shaped openings therein, rail engaging clamps interlockingly received in the T-shaped openings, means for retaining the clamps in engagement with the rails, and a removable fish plate arranged at the opposite side of the rails.
3. In a joint chair of the type described, 15 a base plate, anchoring strips extending from the opposite sides thereof adjacent the ends, an integral fish plate carried by one side of the base plate, the anchoring strips at one side of the base plate having T-shaped openings therein, rail engaging clamps interlockingly received in the T-shaped openings, means for retaining the 20 clamps in engagement with the rails, a removable fish plate arranged at the opposite side of the rails, a depending lip carried by the lower edge of the removable fish plate, and an upstanding lip carried by the base 25 plate of the chair disposed outwardly of the fish plate lip.
4. In a joint chair of the type described, 30 a base plate, anchoring strips extending from the opposite sides thereof adjacent the ends, an integral fish plate carried by one side of the base plate, the anchoring strips at one side of the base plate having T-shaped openings therein, rail engaging clamps interlockingly received in the T-shaped openings, means for retaining the 35 40 clamps in engagement with the rails, a removable fish plate arranged at the opposite side of the rails, a depending lip carried by the lower edge of the removable fish plate, and an upstanding lip carried by the base plate of the chair disposed outwardly of the fish plate lip, the cooperating lips of the fish plate and chair base plate being disposed between the adjacent anchoring strips, and a filler strip interposed between the base plate of the chair and a supporting tie.

clamps in engagement with the rails, a removable fish plate arranged at the opposite side of the rails, a depending lip carried by the lower edge of the removable fish plate, and an upstanding lip carried by the base 45 plate of the chair disposed outwardly of the fish plate lip, the cooperating lips of the fish plate and chair base plate being disposed between the adjacent anchoring strips.

5. In a joint chair of the type described, 50 a base plate, a fish plate formed integral with one side thereof, rail engaging clamps permanently mounted in the base plate and 55 slidable therein for engagement with the base flanges of the rails, and means for holding the clamps in engagement with the rails.

6. In a joint chair of the type described, 60 a base plate, anchoring strips extending from the opposite sides thereof adjacent the ends, an integral fish plate carried by one side of the base plate, the anchoring strips at one side of the base plate having T-shaped openings therein, rail engaging clamps interlockingly received in the T-shaped 65 openings, means for retaining the clamps in engagement with the rails, a removable fish plate arranged at the opposite side of the rails, a depending lip carried by the lower edge of the removable fish plate, and an upstanding lip carried by the base 70 plate of the chair disposed outwardly of the fish plate lip, the cooperating lips of the fish plate and chair base plate being disposed between the adjacent anchoring strips, and a filler strip interposed between the base plate of the chair and a supporting tie.

In testimony whereof I affix my signature.

JOSEPH J. MARKOVICH.
